Primary Examiner — Cathron Brooks*Assistant Examiner* — Ian Whitmore(74) *Attorney, Agent, or Firm* — Nicholas Trenkle; Stites & Harbison, PLLC.(57) **CLAIM**

The ornamental design for a display screen with an icon, as shown and described.

DESCRIPTION

The sole FIGURE is a front view of a display screen with an icon showing the new design.

The broken line showing of the display screen is for environmental purposes only and forms no part of the claimed design.
